UNITED STATES PATENT OFFICE.

JOHN FIELDING, OF GLOUCESTER, ENGLAND.

MACHINE FOR FORGING METALS.

962,705.

Specification of Letters Patent. Patented June 28, 1910.

Application filed August 18, 1909. Serial No. 513,475.

To all whom it may concern:

Be it known that I, JOHN FIELDING, of Sherborne House, in the city and county of Gloucester, in the United Kingdom of Great

5 Britain and Ireland, a subject of the King of England, have invented a new and useful Machine for Forging Metals, of which the following is a specification.

The success which has been achieved by 10 large hydraulic presses in the production of forgings of the heaviest class has led to many attempts to construct smaller hydraulic presses capable of rapid action, with a view to superseding steam hammers for 15 dealing with medium or lighter class forgings. Such so called quick acting forging presses however are much slower than the steam hammer and generally involve more or less complication, and the object of my 20 invention is to combine in one machine the advantages of both press and hammer, so that the first part of the work while the forging is hot may be done by the machine working as a hydraulic press at a moderate 25 speed of about twenty strokes per minute, and the finishing, when the forging is colder, may be performed by the hammer action at a speed of working which cannot be approached by what is called a quick-speed 30 press.

The accompanying drawing shows a convenient form in which my invention may be carried out, but I do not limit myself to this form only, as such a combination of hammer 35 and press may be effected in various ways providing that the hammer piston and hydraulic ram operate relatively to each other in the manner described and shown in the drawing.

40 The accompanying drawing shows a machine according to the present invention in a vertical section.

Referring to the drawing A is the hammer cylinder, with its piston B, stuffing box 45 C, piston rod D, and tup E, F is a hydraulic cylinder in which works the hydraulic piston G fitted with a ram H, which works on the upper end of the hammer cylinder A, and is fitted with piston rings to maintain a 50 pressure tight fit therein. Water is admitted to the top of cylinder F by the passage I and steam or air to the underside of piston G by the passage J. The cylinder A is provided with passages K, L, for the admission 55 of steam or air as is usual in steam hammers.

The operation of the machine is as fol-

lows:—When it is desired to work the hammer only the piston G and ram H are held at the top of their stroke by the pressure of steam or air beneath the piston G. 60 Under these conditions the hammer piston B can be freely worked exactly as in any ordinary steam hammer. To work as a hydraulic press low pressure water is admitted to the upper end of the cylinder F 65 and pressure is relieved beneath the piston G and B provision being preferably made so that somewhat greater pressure remains to act under B than under G, so that contact between the lower surface of ram H 70 and upper surface of piston B is maintained as they fall through the idle part of their stroke. This can be done by suitably restricting the escape of steam or air from beneath piston B to a greater degree than 75 beneath piston G. The upper end of cylinder F being charged with low pressure water as the piston G descends, high pressure is only admitted to produce the required impression on the forging. To effect the upward movement of the hammer 80 and press piston pressure is admitted to the lower ends of both cylinders.

Having now particularly described the nature of my said invention, and in what 85 manner the same is to be performed, I declare that what I claim is:—

1. In a forging machine, the combination of a steam cylinder, hammer, and a hammer piston, with a hydraulic forging 90 press cylinder and a press ram, the press ram being independent from the hammer piston and arranged above the latter to act upon the same when the machine is working as a hydraulic press, substantially as 95 described.

2. In a forging machine, the combination of a cylinder having a hammer piston therein, and steam passages above and underneath the hammer piston, with a superimposed cylinder having a press ram independent from the hammer piston, and a steam passage underneath, and a water passage above the press ram, as and for the purpose set forth. 100 105

In witness whereof I have hereunto set my hand in the presence of two witnesses.

JOHN FIELDING.
